UNITED STATES PATENT OFFICE

2,430,179

PORTABLE PLATFORM

Frank Lanchester, Wootton Wawen, England

Application August 4, 1945, Serial No. 608,984
In Great Britain June 20, 1944

5 Claims. (Cl. 304—29)

1

This invention has for its object to provide an apparatus for use more particularly by brick layers in the construction of dwellings, but applicable also to other analogous uses.

The invention in brief consists in a road vehicle embodying a horizontal frame, at least two platforms thereon, one platform serving to carry the construction and another to carry building materials, means for raising and depressing said platforms independently on vertical lines normal to fixed points on the respective platforms to occupy any of an infinite number of selected positions and means for constantly maintaining the platforms in horizontal positions during said raising and depressing operations.

Referring to the accompanying diagrammatic drawings—

Figure 1 is a side view of one convenient construction of portable apparatus embodying the present invention.

Figure 2 is an end view thereof.

Figure 3 is a side view of a modified construction,

Figure 4 being an end view thereof.

Figure 5 is a side view of a further modified construction, and

Figure 6 is an end view thereof.

In one mode of carrying the invention into effect, as illustrated by way of example in Figures 1 and 2, I employ a base *a* which forms part of a movable vehicle furnished with a pair of wheels *bb*, the said base being provided with four adjustable feet *c*, whereby it can be supported rigidly upon the ground. On this base are secured four rigid upright posts *d* serving to carry a pair of separate and independently movable platforms *ef*, the latter being slidable upwardly or downwardly on the posts. The length of the posts is such as will allow the platforms to be elevated to an extent convenient to the building of (for example) dwellings of one or more stories. One of the platforms serves to carry the constructor, and the other to carry bricks and other building materials. As the platforms are independently movable, they can be moved to different levels, so that the one carrying the materials can be raised to a height above that occupied by the constructor, and thus support the materials in a position in which they can be conveniently handled by him. The latter platform can also be lowered at any time to a position near ground level for reloading as and when required, without disturbing the other platform.

Each platform is actuated by a pair of vertical screw-threaded shafts *k* which pass through

2

screw-threaded parts *g* on the platforms. One of each pair of screws is rotatable by a handle *h* and each pair of shafts are geared together by bevel wheels *i* and shafts *j* also furnished with handles *m*. Also the screw serves as an additional supporting post.

In another construction illustrated in Figures 2 and 3, each platform is carried by three extensible supports *n* constructed in the form of lazy tong. An actuating screw *o* is combined with one end of one of the lower links of one of the supports associated with each platform for extending or contracting this support, and this screw is geared by means of bevel wheels *p* and 15 a shaft *q* with similar screws combined with the other extensible supports. Operating handles *r* are provided for rotating the shafts *o*.

In another construction illustrated in Figures 5 and 6, I employ telescopic tubular supports *s* 20 each adapted to co-operate in the manner of the ram and cylinder of a hydraulic jack, operating liquid being supplied to the interiors of the supports by a pump *t* carried on the base.

It will be apparent that the invention is capable of being carried out in a variety of ways, and is therefore not limited to such examples as those above described, but in all cases at least two independently movable platforms are provided on the one base, and the latter may conveniently 30 form part of a trailer vehicle, though this latter feature is not essential.

By the use of two independently movable platforms, the operations involved in building of dwellings and the like can be greatly expedited 35 and facilitated, and the need for the usual scaffolding and ladders is dispensed with. The constructor is enabled easily to adjust his position progressively to suit the increasing height of the part undergoing erection, and his mate is enabled 40 to keep him supplied with material with a minimum of exertion.

Whilst primarily intended for use in building operations, the invention is not limited thereto, as it may be applied to other analogous uses, and 45 constructional details may be modified to suit different requirements.

I claim:

1. A road vehicle embodying a horizontal frame, at least two platforms thereon, one platform serving to carry the construction and another to carry building materials, means for raising and depressing said platforms independently on vertical lines normal to fixed points on the respective platforms to occupy any of an infinite number of selected positions and means for

constantly maintaining the platforms in horizontal positions during said raising and depressing operations.

2. Portable apparatus as claimed in claim 1, wherein the means for elevating and depressing the platforms independently comprise a plurality of screw-threaded shafts geared together in pairs, suitably positioned operating handles being provided for operating the shafts.

3. Portable apparatus as claimed in claim 1, wherein each of said platforms are carried on a set of at least three lazy-tongs units, means being provided for applying forces to at least one of the said units of each set to effect extension or collapsing of the units associated with each individual platform.

4. Portable apparatus as claimed in claim 1, wherein said means for elevating or depressing the platforms comprise hydraulic ram units.

5. A road vehicle as claimed in claim 1 wherein the frame is mounted on only two road wheels

and is furnished with a plurality of adjustable feet.

FRANK LANCHESTER.
